United States Patent Office

Des. 217,716
Patented June 2, 1970

217,716

ARMCHAIR

Michael D. Tatum, Kirkwood, Mo., assignor to Hellmuth, Obata and Kassabaum, Inc., St. Louis, Mo., a corporation of Missouri

Continuation-in-part of design applications Ser. No. 84,926, Apr. 22, 1965, and Ser. No. 4,587, July 15, 1966. This application Nov. 25, 1966, Ser. No. 5,551

Term of patent 14 years

Int. Cl. D6—01

U.S. Cl. D15—1

FIG.1.

FIG.2.

FIG.3.

FIG.4.

FIG.5.

FIG.6.

FIG. 7

FIG. 8

FIG. 1 is a view in perspective of an armchair embodying my new design;

FIG. 2 is a side elevation of the unit of FIG. 1 as viewed from either side;

FIG. 3 is a front elevation of the unit of FIG. 1;

FIG. 4 is a rear elevation of the unit of FIG. 1;

FIG. 5 is a top plan view of the unit of FIG. 1;

FIG. 6 is a bottom plan view of the unit of FIG. 1;

FIG. 7 is a front elevation of an armchair or arm, seat unit embodying my new design, the sides and back being substantially like that shown in FIGS. 1-6; and

FIG. 8 is a front elevation of an armchair or seat, arm unit embodying my new design, the sides and back being substantially like that shown in FIGS. 1-6.

This application is a continuation-in-part of my co-pending application Serial. No. D. 4,587, filed July 15,

1966, entitled Modular Component Furniture System which in turn is a continuation-in-part of my application Serial No. D. 84,926, filed Apr. 22, 1965, entitled Chair and now abandoned.

I claim:

The ornamental design for an armchair, substantially as shown.
